GAS-LIFT PUMP

James P. Stephens, Clarence M. Rader, Francis E. Steele, and William F. Flood, Oklahoma City, Okla., assignors to Phillips Petroleum Company, Bartlesville, Okla., a corporation of Delaware

Application July 23, 1935, Serial No. 32,798

11 Claims. (Cl. 103—231)

This invention relates to a new method and apparatus for raising liquids from wells, and in particular it relates to an improved type of gas lift pump for raising liquids, such as oil and water, from well and drill holes.

The object of this invention is to provide an improved apparatus and method for raising liquids from wells, which contains a minimum of moving parts, and is positive and reliable in operation.

Other objects of this invention are to provide an apparatus and method for raising liquids from well and drill holes with a minimum amount of gas pressure and loss of volume thereof, and with a lower gas-liquid ratio than heretofore practical, and without the necessity of intermittently releasing or bleeding all of the gas under pressure used in raising the liquid to the surface.

A further object of this invention is to provide a method and apparatus for raising liquids from wells and drill holes in such a manner that the liquid being raised is prevented from flowing back into the well.

A further object of this invention is to provide a method and apparatus for raising liquids from wells and drill holes whereby the liquid being raised is kept in constant motion.

An additional object of this invention is to provide a method and apparatus for raising liquids from well and drill holes whereby the liquid is prevented from running back into the well hole and whereby it is not necessary to overcome the inertia of the liquid each time it is raised toward the surface.

A further additional object of this invention is to provide a method and apparatus for raising liquids from well and drill holes by the use of a gas under pressure in such a manner that no pressure is applied to and held on the strata producing the liquids.

Still further objects and advantages of this invention will be appreciated and become more apparent upon a consideration of the following specification and the attached drawings, forming a part thereof, and wherein like reference characters designate like parts throughout the several views, and wherein,

Fig. 1 is a fragmentary view partially in vertical cross-section and partially in side view illustrating the pump for raising liquids, together with its associated parts, positioned in a well or drill hole.

Fig. 2 is a vertical cross-sectional view of the pump proper illustrating one-half of the mechanism thereof.

Fig. 3 is another vertical cross-sectional view of the pump proper, taken at an angle of 90° clockwise to that shown in Fig. 2.

Fig. 4 is a full horizontal cross-sectional view of the pump illustrated in Figs. 1, 2 and 3, and taken on line 1—1 of Fig. 2.

Fig. 5 is a full horizontal cross-sectional view of the pump taken on line 2—2 of Fig. 2.

Fig. 6 is a full horizontal cross-sectional view of the pump taken on line 3—3 of Fig. 2.

Fig. 7 is a full horizontal cross-sectional view of the pump taken on line 4—4 of Fig. 2.

Fig. 8 is a full horizontal cross-sectional view of the pump taken on line 5—5 of Fig. 2.

Fig. 9 is a full horizontal cross-sectional view of the pump taken on line 6—6 of Fig. 2.

Fig. 10 is a vertical cross-sectional view of a portion of the pump taken on line 7—7 of Fig. 9 and looking in the direction of the arrows, and

Fig. 11 is an enlarged illustration in vertical cross-section of a pipe fitting shown in Fig. 1.

Although this invention is equally adapted for raising various liquids from different types of well and drill holes, one embodiment thereof will now be described in connection with recovering and raising liquids, such as oil and/or water. In order to describe one embodiment of this invention there is illustrated in Fig. 1 the conventional well hole 10 with an outer string of casing 11, and an inner string 12. The lower portion of the inner string of casing 12 terminates adjacent the bottom of the well hole and the producing stratum 13 in the conventional bull plug 14 provided with the apertures 15.

Interposed in the lower portion of the inner string of casing 12 there is provided a nipple or fitting 16 which makes a screw threaded connection therewith, and which is otherwise so constructed as to form a seat 17. The fitting 16 is shown in Fig. 11 and includes the internally screw threaded collars 18 and 19 into which fits the casing 12. The seat 17 is formed with an annular groove 20 opening into which are a plurality of ports 21 communicating with the well hole 10. Above and below the groove 20 is a channel 22 each fitted with a soft metal packing ring 23. The fitting 16 serves as a support and seat for the bottom portion of the pump body 20 and its function will be hereinafter more fully described.

A chamber 30 is formed within the lower part of the casing 12 and is defined by the nipple 16 and a plate 31 having an aperture 32 formed therein. A string of tubing 33 is secured to the lower end of the pump body 20, as shown in Figs.

1 and 3, and extends down into the chamber 30 to a point adjacent the lower end thereof. In the upper end of pipe 33 there is a screw threaded collar or stop 34 into which there is screwed and seated a valve seat 35 and a cage 36 containing the ball valve 37. Below the valve seat 35 the pipe 33 is formed with a plurality of slots or apertures 38 connecting the interior of the pipe with chamber 30. A disc 39 is secured in pipe 33 just below the apertures 38 and is provided with a central aperture 40 through which passes the rod 41 having on its upper end a nut 42 to limit its downward movement to the disc 39. The lower end of the rod 41 is secured to a cylindrical member 43 which fits loosely within pipe 33 and is fastened to the cage 44 formed integral with the valve seat 45 adapted to fit into the aperture 32 of plate 31. A suitable form of packing ring 46 is positioned on the plate 31 to 10 form a tight seal therewith and the valve seat body. A ball valve 47 is contained within the cage 44 and rests upon the valve seat 45 to seal the opening 32. The compression spring 49, contained within pipe 33, bears against the under 15 side of disc 39 and the upper side of the cylindrical member 43, and thereby maintains the cage 44 and seal 46 in the position shown in 20 Fig. 1.

It will be appreciated that the structure above 25 described will permit the liquid, such as oil and/or water, contained in the stratum 13 to accumulate in the bottom of the well hole and when the level thereof and the pressure thereon has become sufficient it will flow into the bull 30 plug 14 through the apertures 15 and unseat valve 47 and flow up into the chamber 30. It is to be understood that while chamber 30 is illustrated fragmentarily in Fig. 1 it is nevertheless of a considerable size and sufficient to accommodate 35 a great amount of liquid. Moreover the structure above described is such that when the pump body 60 is removed from the well, by raising the pipe 59 by which it is suspended, the bottom hole valve 45 and its component parts 40 are also removed.

The pump constituting this invention is of the type that is lowered into the well hole within the casing pipe by means of a string of tubing and is supported above the bull plug and a 45 chamber, wherein the liquid accumulates, by a suitable seat. By means of a string of tubing 59 the pump body, represented generally by the numeral 60, is lowered into the well hole within the casing pipe or pipes and comes to rest as shown in Fig. 1 with the lower end of the pump body 60 supported by the seat 17 of the pipe fitting 16.

While the apparatus comprising this invention is described as a pump it is to be understood that it is of the fluid pressure lift type for raising liquids and does not include any reciprocating plungers, or clap-valves, or the like which are normally present in pumps, but instead utilizes a minor number of parts and only a few 55 moving members in the form of valves. It is believed that a more comprehensive understanding of this invention may be had by first describing generally its method of operation in connection with one embodiment of the structure 60 which may be used therewith. In brief, a gas 65 under pressure, such as air, is forced down into the well hole on the inside of a string of casing pipe so that it will enter a minor port in the pump body to operate a pilot valve, which serves 70 as a control for a main valve. The gas under

pressure here referred to, is intermittently introduced into the casing pipe and is otherwise controlled at the surface by suitable conventional mechanisms. Upon the opening of the pilot valve the gas under pressure can then enter a set of main ports leading into a cylinder within the pump wherein there is contained a main valve in the form of a piston which is designed to control a plurality of ports. One of these ports will, with the valves at a certain 10 position, permit the gas under pressure to enter into a passageway leading to the bottom of the well hole to force the liquid therein up through the pump and to the surface. Another of these ports will, with the valves at a different position 15 permit the gas under pressure, which has been forced into the bottom of the well hole, to bleed off or exhaust so that additional liquid may accumulate below the pump to be raised. Still another of these ports is at times at least partially opened so that gas under pressure is applied to the liquid being raised to give it a considerable lift and to prevent it from draining back into the bottom of the pump, or the string 20 of tubing in which it is being carried to the surface. By virtue of this last function it is not necessary to overcome the inertia of the liquid each time it is forced upwardly toward the surface for the reason that it is at all times kept in constant upward motion. Notwithstanding 25 this function the pump is so constructed that gas under pressure is not applied at all times to the liquid in the well hole to be raised, but is intermittently applied and exhausted so that there are intervals when the liquid can accumulate in 30 the bottom of the well hole as it is forced thereto by the bottom hole pressure. Moreover by virtue of the structure of the pump which will be directly described it is not necessary to bleed or exhaust the entire column of gas under pressure 35 in the tubing each time it is necessary to bleed or exhaust the gas under pressure in the bottom of the well hole for the purpose of allowing the liquid to re-accumulate therein. Additionally, the gas under pressure used to raise the liquid 40 does not enter the well hole and therefore is precluded from exerting any pressure on the strata producing the liquid. This last condition is most important for the reason that if the gas under pressure were applied to the liquid bearing 45 strata the production therefrom would be greatly decreased.

With reference now to the structure of the pump, it will be noted from a consideration of Figs. 1 and 2 that the upper end thereof has 55 connection with a string of tubing 59, the interior of which communicates with a bore, passage or conduit 61 formed internally of the pump body 60 and includes an upper portion 61', a central portion 61, and a lower offset port 61'' which 60 communicates with the interior of pipe 33. The bore, passage or conduit 61 and its components are of varying diameters and are positioned in the pump body 60 as is shown in Figs. 4, 5, 6, 7, 8 and 9. Bore 61 is an eduction conduit and 65 it is therethrough that liquid passes on its way from the bottom of the well, the bull plug, and the chamber 30 to the surface as it is forced upwardly by gas under pressure.

The bore, passage or conduit 62 shown in Fig. 70 3 is offset at the lower end thereof as shown at 62' and is an induction conduit into which through port 63, formed in the upper part thereof, gas under pressure is introduced to be directed to the chamber 30 to raise the liquid 75

therefrom through pipe 33, bore 61, and pipe 58 to the surface. The relative position of the induction conduit 62 within the valve body 60 is shown in Figs. 5, 6, 7 and 8. The lower end of the induction conduit 62' is offset as shown in Fig. 3 and has at the lowermost end thereof a port 64 which connects with an annular space 65 formed between the pipe 33 and the lower end of the pump body 60. This space 65 is in direct communication with the chamber 30 wherein the liquid accumulates as it is forced from the stratum 13 by the bottom hole pressure.

In Fig. 3 there is shown within the pump body 60, a bore 66, which is an exhaust conduit and includes a reduced top portion 66', a central portion 66, and a lower offset portion 66''. The portion 66'' of the exhaust conduit terminates in a port 67 which leads into a space 68 communicating with an annular chamber 69 formed in communication with the annular outlet 70. In the upper end of the central portion 66 of the exhaust conduit there is a port 71, while in the reduced portion 66' of the exhaust conduit there are the ports 72 and 73 which will be described later. It will be noted from a consideration of Fig. 1 that the lower part of the pump body 60 includes a frustoconical end having the tapered portion 74, which when the pump is supported by the fitting 16, makes a sealed fitting with the packing rings 23 and 23 set in the seat 17, thereby bringing the annular exhaust port 70 of the pump in alignment with the groove 20 formed in fitting 16 and in communication with the ports 21 which lead to the space 75 shown in Fig. 1, beyond the casing pipe 12. It is to be understood that the packing rings 23 may be formed on the bevelled face 74 at the lower end of the pump 60, and positioned thereon above and below the annular port 70.

At the upper end of the pump body 60 there is a hollow cylindrical extension 80 having a screw threaded connection with the pump body as at 81, and which at its upper end has a screw threaded connection as at 82 with the reducer 83 to which the pipe 59 is fitted. An interior portion of the extension 80 constitutes the upper part 61' of the eduction conduit.

With reference now to Figs. 2 and 10, it will be seen that in the side wall of the pump body 60 and at a point above the center thereof is a small port 84 which leads into a cylindrical chamber 85 which houses a pilot valve structure. In the bottom of chamber 85 there is formed an outlet 86 and a valve seat 87. A piston 88 having a recessed portion 89 in the top thereof and provided with guide rings 90 is positioned in the cylinder 85 and is of a substantially smaller diameter than the cylinder. The piston 88 is further formed with a valve head 91, and is reciprocably movable in the cylinder 85 to close the port 86. This structure constitutes a pilot valve and its function will be fully described in connection with the complete operation of the pump.

A means is provided to normally retain the valve head 91 upon the seat 87 to keep port 86 closed. This means comprises a collar 92, which is screwed into the upper end of the cylinder 85, and which includes a tubular portion 93 having a screw threaded connection at its upper end with a plug 94 which has a screw threaded central bore 95 to accommodate the threaded bolt 96. The bolt 96 is provided with a head 97 and also has a lock nut 98 which is set to contact the upper face of plug 94. A cap 99 has a screw threaded connection with the upper part of plug

94 to form a housing for the bolt 96. Positioned below the plug 94 and within the upper end of cylinder 93, there is a follower 100 having a flange 101, and a recess 102 in its upper face into which seats the lower end of the bolt 96. A similar follower 103, positioned in the lower end of cylinder 93, is formed with a flange 104 and a recessed portion 105 into which seats the upper end of a pin 106. The pin 106 has rounded ends and the lower end and portion thereof is contained in the recess 89 formed in the cylinder 88. A coil compression spring 107 is housed within the cylinder 93 and the ends thereof are forcibly seated against the flanges 101 and 104 of the followers 100 and 103 respectively. As the plug 94 and follower 100 are normally stationary the spring 107 acts to force the follower 103 and pin 106 downwardly and so maintain the piston 88 in the position shown in Fig. 2 with the valve head 91 upon the seat 87 to keep port 86 closed. This structure for maintaining the valve port 86 normally closed is capable of adjustment, and by removing the cap 99 and unscrewing the lock nut 98 to raise the same, and then by means of the bolt head 97 screwing the bolt 96 down into plug 94 the follower 100 will be forced further down into the cylinder 93 and in this manner the spring 107 will be further compressed and will exert a greater force on the disc 103, the pin 106 and the piston 88, thereby more positively retaining the valve head 91 on the seat 87.

It will be appreciated from a study of Fig. 1 that as air, or other gas, under pressure is forced down into the well hole in the space 110, shown in Fig. 1, between the casing pipe 12 and the pump body 60, that a portion thereof will enter the port 84 of the pump body. When gas under sufficient pressure enters port 84 it will continue therethrough into the lower end of the cylindrical chamber 85 and by virtue of the force that it exerts on the bottom of the piston 88 the same will be raised together with the valve head 91, thereby opening the port 86 through which the gas under pressure will flow.

The upper end of the cylindrical chamber 85 above the piston 88 is in communication with the upper end of the reduced portion 66' of the exhaust conduit. With reference to Fig. 4 which is taken on line 1—1 of Fig. 2, it will be seen that the upper portion of cylindrical chamber 85 is provided with a port 113 which is in communication with port 73 in the exhaust conduit 66' by virtue of the short connecting channel 114. With this arrangement any gas or air under pressure which might leak upwardly in the cylindrical chamber 85 and past the piston 88 to a point thereabove, and which would materially hinder the desired movement of the piston as actuated by the gas under pressure entering port 84, will escape from cylinder 85 to a portion 66' of the exhaust conduit.

With reference now to Fig. 2 it will be noticed that there is formed within the pump body 60 a relatively long cylinder chamber 120 which has a frusto-conical upper end surface 121, shown more clearly in Fig. 10, and which has opening thereto the port 86. Within the cylinder chamber 120 there is a piston structure which includes an upper piston head 122, a lower piston head 123 and a connecting member 124 of reduced diameter. Upon the upper face of the piston 122, as shown in Fig. 10, there is formed a collar 125, the upper end of which is bevelled and is adapted to form a close fit with the upper end surfaces 121 of the cylinder chamber 120.

Formed in the collar 125 are a plurality of relatively small ports 126. The lower piston head 123 has a reduced portion 127 which terminates in a head 128 constituting a seat for the upper end of a compression spring 129. The lower end of the spring 129 rests upon a seat 130 formed adjacent the bottom of the cylinder chamber 120. Into a reduced portion 131 formed at the lowermost end of the chamber 120 there is fitted, as by screw threads, a hollow tubular stop member 132 having formed in the side walls thereof the aperture 133. The stop 132 will serve to limit the downward movement of the piston heads 122 and 123 as the disc 128 attached to the latter will abut the top of the stop member.

With reference to Figs. 9 and 10, the former of which is a cross section of a portion of the pump taken on line 6-6 of Fig. 2, there is shown the cylinder chamber 120 and in a side wall 20 thereof adjacent and in alignment with the ports 126 formed in the collar 125 there is a small port 134 which by virtue of the channel 135 is connected to the port 72 in the upper portion 68' of the exhaust conduit.

25 Formed in an upper side wall portion of the cylinder chamber 120 and adapted to be normally open when the piston 122 is in the position shown in Fig. 2 there is a port 136 which is more clearly shown in Fig. 5. As shown, a short channel 137 connects port 136 of chamber 120 with port 71 of the exhaust conduit 66.

Within the upper portion of the cylinder chamber 120 and below the port 136 is another port 138, which is shown in Figs. 2 and 6, and which 35 will be open at all times regardless of the position of the piston. As shown in Fig. 6 a relatively short channel 139 connects port 138 with port 63 of the gas induction conduit 62.

40 Approximately intermediate of the cylinder chamber 120 there are opening thereto the ports 140 through which gas under pressure as supplied from the surface may enter the cylinder chamber 120 and which are clearly shown in Fig. 7, and are represented in Fig. 2 by the dotted lines. The ports 140 are connected by relatively 45 short channels 141 with the ports 142 which are formed in the outer surface of the pump body 60, thereby establishing communication with the chamber 120 below the piston 123, and the space 50 110 between the pump body 60 and the casing pipe 12. The ports 140 are so situated with respect to the chamber 120 that when the piston heads 122 and 123 are in the position shown in Fig. 2, the piston head 123 will cover the upper 55 half of these ports.

A relatively small channel 143, shown in Fig. 2, connects the cylinder chamber 120 with the liquid eduction conduit 61. The conduit 143 is also shown in Fig. 7 by the dotted lines. When the 60 piston heads 122 and 123 are in the position shown in Fig. 2 the channel 143 will be in communication with the ports 141 through the cylinder chamber 120 so that gas under pressure flowing into the chamber 120 through the conduits 141 will escape into conduit 61 through conduit 143. It is this gas that passes through conduit 143 into the liquid eduction conduit 61 that keeps the liquid being raised therethrough, as will later be described, in constant upward 65 movement to prevent it from draining backwardly.

Leading from the cylinder chamber 120 there is still one other channel which leads into the lower end of the central section of the exhaust conduit 66. As shown in Fig. 2 there is formed

5 at the lower end of the chamber 120, and in the reduced portion 131 thereof, a port 144 which communicates through channel 145 with the port 146 opening into the exhaust conduit 66, as shown in Fig. 8. The complete function of the above 10 described ports will be hereinafter fully explained.

15 Before explaining the complete operation of the above described pump it is desired to discuss the operation of the pistons 122 and 123, which are joined by the reduced member 124 and are movable in unison within the cylinder chamber 120. As previously pointed out the ports 136, 138, and 140 are formed in the side walls of the chamber 120 and are arranged from top to 15 bottom in the order mentioned. Port 136 connects with the exhaust conduit 66 through channel 137 and port 71, as shown in Fig. 5; port 138 connects with the gas induction conduit 62 through channel 139 and port 63, as shown in 20 Fig. 6; and, ports 140 connect with the space 110 between the casing pipe 12 and the pump body 60 through the ports 142 and channels 141, as shown in Fig. 7. With the piston heads 122 and 123 held in the position shown in Fig. 2 25 by the action of spring 129, the exhaust port 136 is open and in communication with the exhaust conduit 66, and the port 138 is open and in communication with the channel 62, and the ports 140 are half closed by the piston 123. This 30 is the normal or neutral position of the pump.

35 Assuming that the various casing pipes 11 and 12 have been set into place within the well hole and that interposed in the lower portion of the latter casing pipe is the fitting 16, now by 40 means of a string of tubing such as the one 59, the pump body 60 having secured to the lower end thereof the pipe 33, and including the valves 31 and 47 together with their associated parts, is lowered into the well hole until the bevelled faces 45 74 formed on the lower end of the pump body 60 come to rest on the seat 17 of the nipple 16. When the pump body 60 is properly in place upon seat 16 the packing rings 23 thereof will form a 50 tight seal with the bevelled face 17, and the annular port 70 formed therein will be between the sealing rings 23 and opposite the annular groove 28 formed in the fitting 16 so that the plurality of ports 21 formed therein will be in alignment and in communication with the annular port 70. 55

With the pump body 60 in the position described the pipe 33 will extend down into the chamber 30 formed in lower end of the casing pipe 12 and the lower end of the valve seat 45 will fit into the aperture 32 formed in the plate 31 and be held securely therein against the packing ring 46 by the spring 49. When the pump and its associated members are initially positioned in the well hole as above described the valves 31 and 47 are upon their seats 35 and 45. 60

Liquids, such as oil and/or water contained in the producing stratum 13, and in other similar strata adjacent thereto, will flow out into the bottom of the well hole or be forced thereinto by virtue of the bottom hole or rock pressure on the 65 liquid. This liquid will accumulate in the well hole around the lower end of the casing pipe 12 and the bull plug 14 and will enter the latter through the apertures 15. When the liquid so accumulated has reached a considerable level or attained a sufficient pressure it will force the ball valve 47 from its seat 45 and flow through the opening 32 formed in plate 31 into the interior of the lower end of the casing pipe 12 constituting the chamber 30. This chamber is of considerable 70 75

length and will accommodate a great amount of liquid, and moreover its size can be readily changed and controlled to meet varying amounts of liquid encountered in the different wells. The 5 valve 37 may be located at any convenient point within the pipe 33, and in the present assembly is positioned within the chamber 30, and while the same is filling up with liquid entering through the aperture 32 this valve 37 will be upon its seat 35. 10 It is to be appreciated that the chamber 30 will become substantially filled with liquid in a relatively short time and with the liquid to be raised to the surface now accumulated therein and the various parts of the pump in the position shown 15 in Fig. 2, and the pump body located in the well hole as described and as shown in Fig. 1, a gas under pressure, such as air, is forced from the surface down the casing pipe in the space 110 formed between the casing pipe 12 and the string 20 of tubing 59, or the pump body 60. The gas under pressure is controlled from the surface and intermittently introduced into the space 110, and when it reaches the pump body 60 a small portion will enter the port 84 and flow into the lower 25 portion of cylinder chamber 85 where it will exert a force on the under side of the piston 88 and raise the same against the action of spring 107, thus unseating the pilot valve head 91 from its seat 87 and opening the pilot port 86 which leads 30 into the top of chamber 120. The gas under pressure will now flow into the top of cylinder chamber 120 and exert a force on the top of piston head 122 sufficient to overcome the action of spring 129, and force pistons 122 and 123 down- 35 wardly in their cylinder 120 until the head 128 meets the top of the stop 132 and thereby limits the further downward movement of the pistons. With the head 128 resting upon the top of stop 132 the upper edge of piston 123 will be below the lower edge of the ports 140 leading into the cylinder chamber 120 between the pistons 122 and 123. This gas under pressure in the cylinder chamber 120 will escape through port 138 into channel 139 and through port 63 into the upper 40 end of the gas induction conduit 62. The gas will continue to flow and be forced down through the conduit 62 and the lower portion 62' thereof and will pass out through port 64 into the annular 45 space 65 from whence it escapes into the chamber 30. The flow of gas under pressure as above described into chamber 30 will be sufficient to cause the ball valve 47 to seat upon the valve seat 45 and thereby close the opening 32 against the entrance of additional liquid. At the same time the gas pressure will be sufficient to force the liquid in the chamber 30 up into the lower end of pipe 33 through the openings 38 formed therein, and cause the liquid to unseat the ball valve 60 37 so that it will flow and be forced by the gas under pressure up into the top portion of pipe 33 and from there into the liquid eduction conduits 61'', 61, and 61' formed in the pump body 60. From the portion 61' of the liquid eduction tube 65 the liquid flows or is forced into the string of tubing 59 which delivers it to the surface. After the gas under pressure has been supplied and is allowed to flow through the pump in the manner described for a relatively short period of 70 time all the liquid in the chamber 30 will have been forced up through the conduits. As the gas under pressure is supplied from the surface at intervals it will at this time be cut off or materially reduced. When this is done the gas pressure will no longer be sufficient to maintain the piston 88 in a raised position and the same will be forced downwardly by the spring 107 thereby causing the valve head 91 to rest upon its seat 87 and so close the port 86. Dependent upon this closing of the pilot valve the spring 129 will force 5 the pistons 122 and 123 upwardly into their normal position as shown in Fig. 2, and by doing so the piston 122 will uncover port 136 which connects, through channel 137 and port 71, the exhaust conduit 66 with cylinder chamber 120, and the upper half of the ports 140 will become closed 10 by the piston 123 leaving the lower half thereof uncovered and opening into the cylinder chamber 120 below the piston 123. With the piston 123 in this position considerable gas under pressure 15 will enter that portion of the cylinder chamber 120 between the piston 123 and the head 128 through the ports 142, channels 141 and ports 140, from whence it escapes through the relatively small passageway 143 into the liquid eduction 20 conduit 61 formed in the valve body. This flow of gas is continuous so long as the various parts of the pump are in their respective positions as shown in Fig. 2, and serves as a means for continuously maintaining the liquid being raised in 25 constant upward motion. By this function of the pump it is not necessary to overcome the inertia of the liquid in the string of tubing 59 each time liquid is raised from the chamber 30 as the liquid is kept in constant upward movement and can- 30 not drain downwardly. Additionally, the gas entering the conduit 61 through the port 143 has a tendency to mix with the liquid being raised and so lighten it, and thereby make it more buoyant and easier to lift. 35 With the pistons in the position as in Fig. 2, gas under pressure will not be forced down into the chamber 30 as port 140 is disconnected from port 138 by virtue of the piston 123 being disposed therebetween. But ports 138 and 136 are 40 in communication as they are now disposed between pistons 122 and 123, and with such conditions existing the gas under pressure may bleed from or be exhausted from chamber 30 through space 65 up into the conduits 62' and 62 and from 45 thence through port 63, channel 139, port 138 and into the cylinder chamber 120 between the pistons 122 and 123. From the cylinder chamber 120 the gas bleeds out through port 136 and channel 137, from whence it bleeds through the lower 50 exhaust conduit 66', through port 67, space 68 and 69, and out through the annular port 70. The annular port 70, as shown in Fig. 1, is in communication with the ports 21 formed in the fitting 16, and it is through these ports that the gas ultimately escapes into the space 15 formed between 55 the casing pipe 12 and the side walls of the well hole. During this bleeding operation it will be noted that substantially only the gas from chamber 30 is exhausted, and the entire volume of gas 60 in the space 110, between the casing 12 and pump body 60 is retained, and it is not necessary to exhaust this gas in order to bleed the gas from chamber 30. 65 As the gas is being exhausted from the chamber 30 the valve 37 will be retained by gravity upon its seat 35. During the exhaustion of the gas, the liquid will again flow from strata 13 or be forced outwardly therefrom by the rock or bottom hole pressure and will accumulate in the 70 chamber 30 as previously described. At about this time the gas pressure apparatus at the surface will re-admit gas under pressure, and on the gas being forced down into the space 110 between the casing 12 and the pump body 60 it will again 75

re-enter the port 84 to lift the pilot valve 91 from its seat. Upon the opening of the pilot valve the pistons 122 and 123 will again be forced downwardly and in so doing the exhaust port 136 is closed by piston 122 and ports 138 and 140 are again brought into communication so that the gas can flow into the chamber 30 as previously taught, to raise therefrom the liquid and force it up into the string of tubing and to the surface.

10 The above described operation and function of the pump constitutes a complete cycle of its operation and by controlling the gas pressure from the surface as by automatic means, and increasing and decreasing it at set intervals the 15 pump can be intermittently operated in a most efficient and satisfactory manner to raise the liquid with a minimum gas input, and with a low gas-liquid ratio.

In conjunction with the above described operation of the pump there are further minor functions which make it practical and cause it to operate in a smooth and efficient manner. For instance, any gas under pressure which may escape upwardly past the piston 88 would tend to 20 act as a buffer for the same and prevent it from being readily raised by the gas entering the port 84. To overcome such a condition any gas getting past the piston 88 into the upper end of cylinder 85 will escape through port 113, shown 25 in Figs. 4 and 10, into the channel 114 and thence into the upper portion 66' of the main exhaust port 66. Furthermore when the valve head 91 of the piston 88 reseats upon the valve seat 87 there will be considerable gas under pressure 30 trapped in the upper portion of the cylinder chamber 120 above the piston 122 which will tend to prevent the pistons 122 and 123 being returned rapidly to their normal positions by the spring 129. To overcome this detrimental condition any gas so 35 trapped will escape through port 134 which is of a lesser diameter than port 84 and which is shown in Fig. 9, into the channel 135 and through port 12 into the upper end 66' of the main exhaust conduit 66. There is also provided a port 144 40 formed at the lower end of cylinder chamber 120. Any gas leaking past the piston 123 and disc 128 into the lower end of the chamber 120 would tend to prevent the pistons 122 and 123 from being readily forced downwardly by the gas under 45 pressure entering the ports 84 and 86, so as to overcome this condition any gas leaking into the chamber 120 below the piston 123 will escape through port 144, channel 145, and port 146 into the exhaust conduit 66.

50 55 What we claim and desire to secure by Letters Patent is:

1. A device for raising liquids comprising a chamber for the accumulation of the same, a conduit in communication with said chamber for the introduction thereto of an actuating gas under pressure, a second conduit in communication with said chamber for the eduction of liquid therefrom, and gas operated valve means to control the flow of said gas through said first 60 named conduit, and a pilot valve operated by variable pressures of said actuating gas to control the admission of gas to said first valve.

2. In a device for raising liquids from wells, a 65 tubing string extending within said well, a check valve adjacent one end of the tubing string, a seat on the tubing string provided with a passage in communication with the exterior of said string, a second tubing string extending within said first named string and forming an annular 70 space therebetween, a pumping element on said

second string having a portion cooperating with said seat to form a liquid accumulation chamber at the lower end of the first named tubing string, a gas induction conduit in said element in communication with said chamber and the 5 annular space for the induction of gas pressure to said chamber, a liquid eduction conduit in said element in communication with said chamber and said second tubing string, a check valve in said last named conduit, a gas exhaust conduit in 10 said element in communication with said gas induction conduit and said seat passage, and valve means in said element for controlling the admission of gas to said chamber and the exhaust of gas therefrom.

15 3. In a device for raising liquids from a well, a tubing string extending within the well and provided with a check valve adjacent one end thereof, a source of gas under pressure in communication with said tubing string, a seat on 20 said tubing string, a second tubing string within said first named string, a pumping element on said second string provided with a portion cooperating with said seat to form a liquid accumulation chamber in said first named tubing string, 25 a conduit in said element for the conduction of gas pressure from said first named tubing string to said chamber, a conduit in said element for the conduction of liquid from said chamber to said second tubing string, and means in said element to control the flow of gas through said gas conduction conduit.

4. A pumping apparatus for raising liquids from wells comprising in combination, a tubing string extending within the well to a point below 30 the fluid level therein and provided with a check valve adjacent one end thereof, a source of gas under pressure in communication with said tubing string, a seat on said tubing string, a second tubing string within said first named string, a pumping element on said second string adapted to cooperate with said seat to form a liquid accumulation chamber in said first named tubing string, a conduit in said element for the conduction of liquid from said chamber to said second tubing string, and means in said element responsive to changes in gas pressure in said first named tubing string to control the admission of gas to said chamber through said gas conduit.

5. In a pumping element for a pumping apparatus including a body having gas and liquid passages therein, a valve chamber in said body, a main valve slidable in said chamber to control the flow of gas through said gas passages, a gas pressure operated pilot valve controlling the admission of gas under pressure to one side of said main valve to operate the latter.

6. In a pumping element for use in well pumping apparatus utilizing gas under pressure as the actuating medium, a body having gas and liquid 60 passages therein, a valve chamber in communication with said gas passages, a gas-pressure actuated main valve for controlling the flow of gas through said passages, and means responsive to variations in gas pressure to control the admission of gas to actuate the main valve.

7. In a pumping element for use in well pumping apparatus in which gas under pressure constitutes the pumping medium, a body having gas and liquid passages therein, a main valve in 70 said body actuated by gas pressure for controlling the flow of gas through said passage, and means adjacent said main valve responsive to changes in gas pressure to control the admission of actuating gas to said main valve.

8. In a pumping apparatus to be operated by gas under pressure, a pumping element comprising a body member provided with gas induction, liquid eduction, and gas exhaust passages therein, a main valve chamber in communication with said gas induction and gas exhaust passages and provided with gas admission ports in communication with the exterior thereof, a valve slidable within said chamber constructed and arranged alternately to place said gas admission port in communication with said gas induction passage, and said induction passage in communication with said exhaust passage, and means operated by variable pressures of said actuating gas to control the admission of gas to said first valve.
9. A device for raising liquids comprising a chamber for the accumulation of the same, a conduit in communication with said chamber for the introduction thereto of an actuating gas under pressure, a second conduit in communication with said chamber for the eduction of liquid therefrom, a gas operated valve means to control the flow of said gas through said first named conduit and means operated by variable pressures of said actuating gas to control the admission of gas to said valve means.
10. In a pumping apparatus to be operated by gas under pressure, a pumping element comprising a body member provided with gas induction, liquid eduction and gas exhaust passages therein, a main valve chamber in communication with said gas induction and gas exhaust passages and provided with gas admission ports in communication with the exterior thereof, a valve slidable within said chamber constructed and arranged alternately to place said gas admission port in communication with said gas induction passage, and said induction passage in communication with said exhaust passage, and means operated by variable pressures of said actuating gas to control the admission of gas to said valve.
11. In a pumping apparatus to be operated by gas under pressure, a pumping element comprising a body member provided with gas induction, liquid eduction and gas exhaust passages therein, a main valve chamber in communication with said gas induction and gas exhaust passages and provided with gas admission ports in communication with the exterior thereof, a valve slidable within said chamber constructed and arranged alternately to place said gas admission port in communication with said gas induction passage, and said induction passage in communication with said exhaust passage, and a pilot valve operated by variable pressures of said actuating gas to control the admission of gas to said valve.
